UNITED STATES PATENT OFFICE.

REBECCA B. PRICKETT, SAMUEL A. ATKINSON, AND COOPER H. PRICKETT,
OF MOUNT HOLLY, NEW JERSEY, EXECUTORS OF EDWARD L. PRICKETT,
DECEASED.

DESIGN FOR A PEN AND PENCIL HOLDER.

SPECIFICATION forming part of Design No. 31,458, dated August 29, 1899.

Application filed June 20, 1899. Serial No. 721,273. Term of patent 7 years.

To all whom it may concern:

Be it known that we, REBECCA B. PRICKETT, SAMUEL A. ATKINSON, and COOPER H. PRICKETT, citizens of the United States, residing at 5 Mount Holly, in the county of Burlington and State of New Jersey, executors of the estate of EDWARD L. PRICKETT, deceased, late a citizen of the United States, residing at Mount Holly, in the county of Burlington and State 10 of New Jersey, (as by reference to the duly certified copy of the letters testamentary here-to annexed will more fully appear,) do hereby declare that EDWARD L. PRICKETT invented and produced a new and original Design for 15 a Pen and Pencil Holder, of which the following is a specification.

The invention relates to a new and original design for a pen and pencil holder; and it has for its object to provide a design of this character which will be both useful and ornamental.

The leading feature of the design resides in a holder comprising a flat base-plate having a rounded bottom portion and provided 25 with a top portion having a straight horizontal upper edge and straight inclined side edges, said base-plate being provided with parallel side edges extending from the inclined edges of the top portion to the rounded 30 bottom portion and a pair of longitudinal pockets rectangular in cross-section and provided with pyramidal lower ends.

In the drawings, Figure 1 is a perspective

view of a pen and pencil holder, showing the new and original design. Fig. 2 is a front elevation of the same. Fig. 3 is a cross-section on the line 3 3 of Fig. 2.

Referring to the drawings, 1 designates a base-plate having parallel side edges and provided with a rounded lower end 2, and having its upper end provided with a straight top edge and truncated corners 3, having straight inclined edges extending from the parallel side edges to the horizontal top edge. The parallel side edges, which are straight, extend 45 from the inclined side edges to the rounded lower end. The base-plate is provided with a pair of longitudinal pockets 4, rectangular in cross-section and having pyramidal lower ends 5. 50

What is claimed is—

The design for a pen and pencil holder herein shown and described.

In testimony that we claim the foregoing as the invention of EDWARD L. PRICKETT we have hereto affixed our signatures in the presence of two witnesses.
